To all whom it may concern:

Be it known that I, EUGENE IRVING HANSON, a citizen of the United States of America, and a resident of New Rochelle, in the county of Westchester, State of New York, have invented a new, original, and ornamental Design for a Textile Fabric, of which the following is a specification, reference being had to the accompanying drawing, showing my design.

The drawing shows a face view of a portion of fabric bearing my design.

In the drawing *a* indicates a disk, *b* a rectangle having one of its ends curved, *c* a rec-

tangle having its surface interrupted by figures *d*, *e* and *f* defined by straight lines and the periphery of the disk, the figures *a*, *b*, and *c* being so positioned with respect to each other as to give the appearance of being superimposed, the whole being produced upon a white background *g*.

The design is intended to be repeated on the fabric.

I claim:
